Primary Examiner — Jennifer Rivard*Assistant Examiner* — April Rivas(74) *Attorney, Agent, or Firm* — Cooper & Dunham LLP(57) **CLAIM**

We claim the ornamental design for a luggage bag, as shown and described.

DESCRIPTION

FIG. 1 is a front top perspective view of a luggage bag, in accordance with the present design;

FIG. 2 is a top view of a luggage bag;

FIG. 3 is a bottom view of the luggage bag;

FIG. 4 is a front view of the luggage bag;

FIG. 5 is a rear view of the luggage bag;

FIG. 6 is a left side view of the luggage bag; and,

FIG. 7 is a right side view of the luggage bag.

The shading represents contour of the claimed design.
